Cable Company, Inc., a corporation of Delaware

Application January 6, 1927, Serial No. 159,261
Renewed October 22, 1935

25 Claims. (Cl. 117—59)

This invention relates to improvements in the art of "wire rope," which name commonly defines the strong, die-squeezed compacted metallic-wire rope structures in general industrial use for heavy duty as in the mining, logging and oil industries, in general construction including bridges, hoisting, conveying and marine operations, and in industrial plants generally, etc., the wire rope construction for such uses principally consisting of a wire rope including a plurality of metallic wire "strands" or outer elements extending in helices around a central element commonly called the "core" or "center" of the wire rope structure, the assembly of strands (outer elements) and core (center) as a whole possessing the high longitudinal resilience necessary for momentary longitudinal rope-yielding to abrupt applications of the heavy service loads and consequent avoidance of rope-breakage thereby; the strands commonly numbering six; each strand consisting of a plurality of metallic wires commonly of steel and commonly numbering eighteen stranded together in helices in layers around their own central element, which commonly is another steel wire; and the group of strand-helices being, in commercial production, compacted against the core by pulling the assembly through the assembling or "closing" die thereby causing powerful die-squeezing compression of the strands laterally against the core, toward the limit of die-compression causing injuries to the outer strand-wires by traveling contact with the hardened steel die-wall as the assembly is pulled through the squeezing die by the "closing tension." The necessary longitudinal resilience of wire rope structure is caused in general by the springiness of the individual wire helices. Generally in wire rope there is a center or core comprising fibrous material for the purpose of increasing the longitudinal rope-resilience and also of increasing the rope-flexibility; and commonly such fibrous core consists of ordinary commercial so-called "hemp rope" consisting of vegetal fibers such as manila, jute, sisal, cotton, etc., and therefore having high longitudinal resilience.

Wire rope and wire rope structures in general heretofore have been manufactured commercially in two types respectively known as (1) "ordinary" and (2) "pre-formed" or "pre-shaped." Ordinary rope, according to the previous methods of manufacture thereof, has been subject to occurrence of so-called "rope-faults" of various kinds during either or both pre-installation handling or during service under the heavy loads; such faults develop into injuries during the heavy service, and such injuries shorten rope-life by causing premature breakage and meanwhile reduce safety during service. The various rope-faults to which wire rope structures are subject are caused either or both by (1) excessive tend-

encies of the strands during pre-installation handling to spring into displacements constituting the "faults," i. e., lack of inertness, or by (2) lack of equi-stress or balanced relations of strands and core which, during the heavy service for 5 which wire rope structures otherwise are well adapted, results in concentration of excessive proportions of the heavy service loads upon one or more of the strands or on the core, so that core and strands cannot properly cooperate in 10 the sense that each shares properly with the others in sustaining the service loads, the result being rope-faults and premature rope-breakage.

According to the invention novel wire rope structures are produced which possess the advantages and lack the disadvantages above set forth. The products are inert in the sense that they are in a condition substantially free from internal stresses which cause or tend to cause the helical wires or strands, when not tied together, to depart from the shapes and positions proper in ideal structures, and in character the products are substantially dead-lay, inert-lay, stress-free and neutralized. In addition, the helical outer elements and the center element or 20 core all are in balanced stress relation with one another, so that each shares properly with all the others in sustaining service loads, and the wire rope structures possessing said characteristics of inertness and balanced relations also are 25 capable of long resilient service life.

According to the invention, such novel wire rope structures are produced by applying to a previously assembled wire rope structure, tensioning stresses of certain magnitudes sufficiently 35 but not excessively high as hereinafter defined. To effect balancing, in addition to inertness, these tensioning stresses preferably are applied to each successive portion of the length of the assembly as it travels from the squeezing closing 40 die to the wind-up reel, and preferably in a series of steps of progressively increasing magnitudes of tensioning; and also, for effecting balancing, in addition to inertness, the series of tensioning steps preferably is employed with a 45 corresponding series of flexings of the assembled wire rope structure as a whole. In any case the tensioning treatment preferably is applied to the assembly in such way that it does not affect the stresses acting on the squeezing closing die 50 wherein the elements are assembled, and in such way that it causes the application of stresses to the individual helical wire outer elements which are different in kind from and of larger magnitude than the stresses acting in the die. That 55 is, the tensioning treatment, being applied to the assembly wherein the helical outer elements already have been laid around center or core, causes the individual helical elements to be simultaneously both subjected to tensioning and 60

to be by the tensioning compressed against center or core. Thus, with the result of producing equi-stress or balanced relations of all the elements, the tensioning of the helical outer elements tends 5 to equalize the strand-lays relative to one another and with respect to the center; and, with the result of imparting a metal-set deformation to the helices producing effective inertness, the compression of the helices against the center caused 10 by the tensioning, reacts with the radial resistance of the center to such compression during the continued tensioning of the helices, so as to stress the metallic helices beyond their elastic limits into the desired substantially inert condition lacking excessive springiness. For the purpose 15 of producing balanced relations, in addition to inert condition, in a wire rope having a center or core of the fibrous or hemp-rope type, the employment of a plurality of successive flex- 20 ings of the assembly in connection with the series of tensionings of progressively increasing magnitude, is particularly useful for several reasons, (1) the flexings are particularly effective in causing shifting movements of the helical strands 25 from non-balanced into balanced relations, (2) the initial less heavy stressings of the series cause the strand-helices to be less heavily compressed against the core and therefore preserve comparative freedom of the strand-helices for 30 their shifting balancing movements caused by the flexings and tensionings, (3) the initial radial yieldability of the hemp-rope type core cooperates with the initial less heavy stressings in preserving said freedom of the strand-helices for 35 balancing movements, and (4) in the later, heavier stressings of the series, the desired metal-set deformation of the strand-helices into inert conditions is effected by the then more powerful internal reactions between strands and core at 40 a time after the balancing has been substantially effected by the earlier less heavy stressings of the series, so that the later more substantial deformation does not interfere with the earlier more substantial balancing; the internal re- 45 actions which cause the more substantial deformation being caused by the later, heavier stressings as the result of the then-existing greater radial resistance by the more highly compressed and dense fiber core to the increasing 50 compression against such core by the strands under the then higher tensionings. The result of the serial treatment in any case is to produce better relations of balance than can be produced by a single tensioning of the assembly of sufficient magnitude to produce optimum deformation to inertness. The result of the serial treatment which includes the multi-flexing is to produce 55 better relations of balance in a wire rope having a fiber or hemp-type core than can be produced, in the lack of multi-flexing, even by a series of tensionings of progressively increasing magnitude. The relative extents of balancing and deformation in a given product are dependent upon the previous condition of the assembly subjected to the processing; but in any form of the processing the balancing and de- 60 forming operations are substantially simultaneous so that in any form of the product the conditions which cause inertness are also the cause 65 of the setting of the balanced stress relations into the product as a permanent characteristic thereof.

In addition to the process, the invention includes also the novel wire rope possessing the characteristics described herein, and the novel

arrangements of apparatus units employed in the processing.

In the novel arrangements of apparatus units, the several units as individuals may be employed in the forms heretofore employed in the wire rope 5 industry.

The best examples of the invention known to us are illustrated by the drawings, some of which are more or less diagrammatic for the purpose of most clearly explaining the principles of the 10 invention by simple and clear illustrations not confused by relatively unimportant details.

Fig. 1 is a diagram of one exemplification of the processing and of the apparatus; Fig. 2 a drawing in transverse section of a preferred 15 form of the various forms of the new product and consisting here of a wire rope comprising radially yielding center or core of hemp, jute, manila, or the like vegetal fibre; Fig. 3 a sketch illustrating the novel metal-set strand-deforma- 20 tion or inert or dead-lay strand-construction resulting from the processing; Fig. 4 a sketch in transverse section illustrating the initial core-condition of the preferred radially yielding core of Fig. 2 previous to processing of the assembled 25 wire rope which results in the product of Fig. 2; Fig. 5 a sketch in like section of the same radially yielding core showing it separately in the same condition as in Fig. 2 after processing of the 30 assembled rope including such core; Fig. 6 a sketch in like section of the same radially yielding core illustrating its condition without injury after long service of the rope including it, but the core being resiliently "dead" as the result of long service under the heavy loads; Fig. 7 an 35 elevation of the wire rope of Fig. 2 also illustrating its good condition without rope-faults or injuries after having been handled previous to installation for service, and after a long life of 40 heavy-duty service; Fig. 8 another form of our novel product similar to that of Fig. 2 save for having a core of initially smaller diameter than the core of Fig. 4 in the rope of Fig. 2 before the processing hereof; Fig. 9 a diagram supplementing Fig. 3 and illustrating more clearly the nature 45 of the novel metal-set strand-deformation or inert strand-construction resulting from the processing; and Fig. 10 a diagram exemplifying the principles of the processing in a different form, and the novel arrangements of apparatus 50 units therefor.

Fig. 10, left, at lay-plate LP and closing or squeezing die CD, illustrates the preferred initial processing hereof which is the well-known previous commercial assembling and die-squeezing 55 method of producing wire rope structures in general.

An excellent example of the balancing and de-forming processing of assembled wire rope structures is shown in Fig. 1 between CD and POI 60 where POI is any suitable power-driven pull-out or draw-off drum, as used in the wire rope art to pull the wire rope structure in process out of CD. Here POI is driven with sufficient power to pull the wire rope structure, not only through 65 squeezing die CD but also around a plurality of sheaves 1, 2, 3, of diameters small relative to POI in substantially the proportions shown, and to pull individually the strands S of wires W and core R for a wire rope from their reels 70 at left (not shown) and through lay-plate LP. Each portion of the length of the rather stiff wire rope being pulled by POI from CD and around the successive relatively small sheaves, thereby is powerfully flexed a plurality of times 75

in relatively sharp bending angles by the tensionings on the rope by power from PO1, so that each such portion of the rope-length is subjected repeatedly to powerful flexing stresses under the successive tensionings; and the simultaneous balancing and deforming actions on strands and core are progressive. The presence of vegetal fiber core R, Fig. 4, in the assembled rope being processed, imparts the sufficient flexibility to the 10 stiff and otherwise much stiffer wire rope which is necessary to permit its said relatively sharp-angled flexings. The relatively small sheaves are mutually offset as shown, so that successive sharp-angled flexings of the assembled wire rope are 15 in opposite directions. In order to pull the rope-assembly not only through CD but also around the successive sheaves 1, 2, 3, in the above relatively sharp flexings around the relatively small sheaves, the drum PO1 is driven with greater 20 power than when there are no flexings as in Fig. 10, other conditions being equal. The result is that in Fig. 1 the tensioning on the rope-assembly passing from the last sheave 3, to PO1, is substantially higher than that in Fig. 10 between 25 CD and PO1; and correspondingly, since in Fig. 1 a portion of the greater power of PO1 in Fig. 1 than in Fig. 10, is usefully consumed in the successive flexings in the direction from PO1 toward CD, the tensioning between the flexings at 30 2 and 3 causing the flexing at 2, is lower than between 3 and PO1; the tensioning between 1 and 2 and causing the flexing at 1, is lower than between 2 and 3; and the tensioning between CD and 35 1 and causing the assembly to be pulled through CD, is the lowest of the series of tensionings acting between CD and PO1. Correspondingly, since such tensionings provide the power for the respective powerful flexings, the 40 flexing or bending stresses of the series in the direction from PO1 to CD likewise are of progressively decreasing magnitude, other things being equal. That is, in the opposite direction, which is the direction of rope-travel, (see arrow), all the stressings of the series, both tensionings and flexings, are of progressively increasing magnitude, other conditions being equal. The result is that each portion of the length of the rope-assembly traveling from CD to PO1 is subjected 45 successively to a plurality of flexing and tensioning stresses of progressively increasing magnitude. An object and result of this is the avoidance of such premature deformation of strands or core by tensionings during the earlier, less heavy stressings as would antagonize or oppose 50 the desired balancing action during the earlier stressings when the fiber core yet is so relatively yieldable radially as to yield to the earlier, less heavy stressings and by such yielding preserve the freedom of the strands for their relative shifting 55 balancing movements thereof. Nevertheless, the several stressings of the series are sufficiently powerful to effect their own proportion of both the balancing and permanent deformation. The stressing at each of the successive flexings is 60 made sufficiently powerful by the combination of the relatively long rope-arcs involved in each flexing, with the relatively sharp angles of flexing; the long rope-arcs being caused by the offset relations of the sheaves, and the relatively sharp 65 flexing-angles being caused by the relatively small diameters of the sheaves; one result being that the flexed rope-portions are subjected to stresses which are more powerful than those 70 acting in squeezer CD; and another result being a different kind of stressing of the flexed 75

rope-portions than the stressing inside CD, as follows. At each flexing, the strands of the flexed rope-portions are bent at relatively sharp angles to the relatively abrupt contour of the relatively small sheave; and this operation involves 5 subjection of the core to powerful compression by the strands, and also involves powerful tensioning of the flexed strands during the time of such core-compression by the strands. It is this combination of core-compression by the 10 strands and simultaneous strand-tensioning during the core-compression, all during the flexing of the assembly, which produces the balancing and deforming operations respectively but simultaneously. The tensioning of the strands on 15 the outer or convex portions of the flexure is higher than during the axial tensionings between successive flexings around successive sheaves. The tensioning of the strands on the inner or concave portion of the flexure is lower than the 20 axial tensioning between sheaves causing the flexure. In a given flexing, however, there is core-compression only by the strand lying against one side of the core, i. e., by the strands lying on the outer or convex portion of the flexed assembly; and similarly as to the higher tensioning of the strands, that tensioning is effective on such strands which in a given flexing extend on the outer or convex portion of the flexed assembly. The offsetting of the successive sheaves 25 however causes flexing in successively opposite directions, so that in the successive flexings the strands lying adjacent each side of the core successively lie on the outer or convex side of the flexing. The effect of the progressively increasing 30 magnitude of the stresses in the successive flexings is progressively to increase the core-compression or density by the strands and to increase the strand-tensioning at the flexed portions being compressed against the core. As 35 these stresses increase, the increasing resistance of the increasingly dense center or core to the increased strand-compression against it causes the strands to be deformed beyond their elastic limits by the increasing tensioning on them at 40 their flexed portions, into strand-helices of larger and larger metal-set diameters as the successive stresses increase progressively in magnitude. This metal-set deformation of the plurality of 45 strands in the assembly, at each flexing and 50 under the effect of tensioning during flexure, is generally analogous to the action involved in making a wire spring by tensioning a resilient metallic wire while bending it around a mandrel. Here, however, as the compressions by the 55 flexed strands on the core and the tensioning on such flexed strands, are increased in the successive flexings, all the plurality of strands progressively are stressed again and again beyond 60 their elastic limits into metal-set helices of larger and larger diameter. These permanent strand-deformations into helices of permanently larger diameter take place while the helices temporarily are being stretched into temporary smaller diameter. 65

While the strands thus are being deformed into new shapes by the successive flexings of the assembly, they also are being shifted simultaneously into new adjusted positions of equi-stress or balanced relation with one another and with the 70 core. All "ordinary" wire rope having a commercial "hemp-rope" of fibrous or "vegetal" core is subject to non-balanced relations because of the irregularities along its length including varying diameters. The formation of the strand- 75

helices, without substantial deformation, in the squeezer CD, while the strands are being assembled around the core, puts the strands in out-of-balance relations with one another. For the purpose of producing balanced stress relations during the operation of deforming the strands while in the assembly, we have found that the above multi-flexing treatment is especially advantageous when the assembly includes a core of the commercial hemp-rope type which heretofore has been the cause of non-balanced relations. The advantage of this application of the multi-flexing process to an assembled wire rope being a hemp-rope type core is that such a core initially possesses radial yieldability to the earlier, less heavy strand-compressions in the earlier flexings, so that thereby there is less powerful binding of strands against core, the result being that the strands during the earlier flexings are relatively free for the relative shifting strand-movements which are involved in the balancing operation; and yet, during the later flexings, under the then heavier strand-compressions on core caused by the heavier tensionings on the flexed strand-portions, the core-resistance to such strand-compression is sufficient to cause deformation of the strands while they are positioned in their balanced relations. Thus, previous to such strand-deformation as otherwise would prevent desired balancing, the desired balancing is effected by the earlier flexings under less core-compression by flexed strands and less strand-tensioning during flexing, and while the core, previous to the later heavier compression by the strands, yet is more yieldable radially to the lighter strand-compressions thereby allowing strand-movements to balanced relations under the balancing stresses of the flexings. In the balancing operation the slack in any strand or strands in the assembly is in effect "ironed" out backward (leftward, Fig. 1) toward CD, thereby removing a large part of the discrepancies between length of strand-lays and to that extent putting the strands in balanced relations with one another. This ironing out of strand-slacks involves arresting the same between CD and the first flexing at 1, thereby preventing travel of strand-slacks with the wire rope rightwardly beyond 1; the non-slack strands in the traveling assembled rope in effect catching-up with the strand or strands of which the slacks are being arrested. This ironing operation is the effect of the lighter earlier flexings, acting on the assembly having a center or core which radially yields at such time so as to permit the strand-slack ironing movements which the flexings tend to cause. The other adjusting or shifting relative strand movements also occur during the multi-flexing as the result of the radial yielding of the core to its compression by the strands during the increasing strand-compressions in the successive flexings. The increasing strand-compressions form grooves in the core of progressively increasing depth, so that the strands move broadside or laterally further and further toward the center of the core, thereby further improving the balanced relations of strands relative to one another and improving the relations of strands relative to the irregularities of the commercial hemp-rope or fiber core. The successively opposite flexings of progressively increasing strand-compression on the core cause the strands to be worked deeper and deeper into the core and constitute an effective "kneading" operation co-operating with the strand-slack ironing action

in establishing the desired balanced relations. As the kneading operation progresses under the progressively increasing strand-compressions on the core, the core-density correspondingly increases, the entire core is deformed into a slightly smaller diameter and the helical core-grooves receiving the strands become permanently deformed into progressively increasing depths, as at GG, Fig. 5, with extruded core-projections P, all as distinguished from the initial core condition in Fig. 4. The resulting increase of core-density caused by the processing is illustrated by the greater core-density in Fig. 5 than in Fig. 4. This permanently deformed dense core condition is advantageous in several respects. The radial core-projection P, while not excessively long, nevertheless extends sufficiently far into the inter-strand spaces to support the strands in spaced-apart condition preventing strand-to-strand contacts and thereby providing for rope-pliability. Also the great core-density permits substantial increase of resilient core life and therefore resilient rope-life in that it permits the use of a core of larger initial diameter than heretofore has been practicable in an "ordinary" type wire rope of given diameter, because in the lack of the permanent core density as in Figs. 5 and 2 and 8 as compared with Fig. 4, the higher radial resilience of a larger core tended to push the strands away and increase the susceptibility to pre-installation faults; but in the preferred form of Fig. 2, with initially larger core R than the initial diameter of core R₁ of Fig. 8, the initially larger core can be used without such disadvantage because of the effect of the deeper grooves GG coupled with the deformed strand-helices EV to be described, whereby the inert characteristic of the product is obtained, all with the result that the resilient life of the product can be increased by the use of the larger core. This is illustrated in Figs. 2 and 8 which show the same wire rope save for the initially larger core R in Fig. 2, illustrated here by the denser stippling of core R in Fig. 2 than that of core R₁ in Fig. 8, the denser stippling in Fig. 2 illustrating the denser condition of larger core R than of smaller core R₁ in Fig. 8. That is, the two completed wire rope products of Figs. 2 and 8 are of the same outside diameter, but the assembly in Fig. 2 with initially larger core has been subjected to higher processing stresses than that in Fig. 8 with the results that the core-grooves are deeper and that the higher strand-compressions on the initially larger core R of Fig. 2, in addition to the deeper seats of the strands in the deeper grooves, have so reduced the effective diameter of the core that the wire rope of Fig. 2 has substantially the same outside diameter as the wire rope of Fig. 8 having the initially smaller core; although the greater mass of longitudinally resilient core-material in Fig. 2 causes longer life of the product of Fig. 2 than of the product of Fig. 8. In a wire rope having a total diameter of one inch and a fiber core of half inch diameter, an increase of core diameter of only a thirty-second of an inch will increase the life of the wire rope substantially, and that is permitted by the invention.

The principal advantage, however, of the compressibility of the fiber core by the strand-compressions in the multi-flexing treatment, is that of the increasing radial resistance of the core as its density is increased by the increasing strand-compressions in the successive flexings; for it is the increased radial resistance of the

increasingly dense core which increasingly opposes the increasing strand-compressions and thereby, under the increasing tensionings on the flexed strand-portions, sets up the reaction inside the wire rope which stresses the strands beyond their elastic limits and deforms them into metal-set helices of larger and larger diameter simultaneous with the above progressive balancing movements of the strands during the multi-flexing; for in the case of any center or core, the greater the radial core-resistance to strand compression and the greater the strand-tensioning during great radial core-resistance to strand-compression, the greater will be the strand-deformation to helices of larger diameter.

Simultaneously with the above deformation of strands and core during the multi-flexing treatment of the assembly having a vegetal or fiber core for the purpose of most effective utilization of the flexing stresses for the purpose of effecting balancing, the balancing operation is taking place preferably under the following conditions as shown. The first flexing of a given portion of the wire rope assembly is at 1 where the core-compression by the strands and the tensioning of the strands at the place of flexure are the lowest between CD and PO1, so that thereby there is avoided initially all heavier stressing such as later at 2 or 3 which if so applied at 1 nearer CD might cause undesirable alteration of the uniformity of critical assembling stresses acting inside CD and undesirable alteration of the effect of the stresses in CD in producing uniformity of strand-lays. By this arrangement the assembling operations inside CD cannot be affected by the later, heavier stresses of the series by which is effected the deformation of strands and core; the initial balancing operations being conducted under axial tensionings of the wire rope between sheaves which are not much greater than the tensionings in CD, and being conducted intermediate the assembling in CD and the deformation by the later stressing after the first flexing at 1. As shown also, the first flexing at 1 preferably is produced as close as practicable to CD, the advantages of this being two; first, the "ordinary" type in its condition of emergence from CD possesses minimum deformation of strands and core and therefore there is minimum opposition to the flexing stresses causing the ironing out of strand-slacks, and second, the first flexing at 1, close to CD, is produced before any prolonged rope-tensioning between CD and flexing 1 which would cause deformation opposing the ironing action of the flexings. As shown also in Fig. 1, the sheave-set as a whole is located closer to CD than to PO1 so as to complete the balancing and deformation by the series of flexings on each portion of the length of the assembled rope as soon as practicable after its emergence from CD and before the rope finally is subjected to any prolonged or high axial tensioning as between 3 and PO1 which is the highest between CD and PO1 and useful in effecting further deformation after completion of balancing by the flexings and partial deformation.

Preferably the wire rope which is processed hereby, for most effective strand-shifting balancing action is of the "ordinary" type, wherein, as shown at left, Figs. 1 and 10, the strands S are pulled in straight condition to CD without any deformation of individual strands or core previous to assembly, as of strands in the "pre-formed" type, and with only slight if any deformation of

strands or core by CD wherein the straight strands entering CD are bent laterally, without substantial metal-set deformation into helices around the core and preferably therein squeezed by CD into as compact an assembly with the core as is practicable without injuring the outer wires of the strands traveling in contact with the usual hardened steel wall of die CD. A wire rope in such initially compact condition is well adapted to be balanced by the processing hereof, because of its possession of minimum deformation of strands or core interfering with the relative shifting balancing movements of the strands which the processing stresses can and do produce unless there be premature excessive deformations of strands or core as by excessive strand pre-deformation in advance of assemblage in CD as in the case of the pre-formed type as heretofore produced with strands pre-deformed substantially to core-diameter. The "ordinary" type in said sense also is well adapted to be balanced by the processing hereof because the strands at the time of processing of the assembly already are in place around the core, so that the balancing of the strands relative to one another is effected with reference to the core around which they already are assembled as distinguished from the pre-formed type wherein the strands previous to assemblage individually and separately are given metal-set deformations to predetermined like diameters so large as to approximate the diameter of the core around which they later are to be assembled, as at B, Fig. 9. Furthermore, commercial "hemp rope" employed as the core of wire rope, possesses irregularities including varying diameters along its length. By the application of the flexing stresses hereof to an assembled wire rope preferably having no pre-deformation of strands and in no case having excessive strand-deformation, the strands are put in balanced relations with the core during a time when the strands extend around the very core with relation to which balancing is desired, and during the time while the strands are being put in balanced relations with one another; and by the application of the processing flexing stresses to a wire rope assembly, such as the "ordinary" type, possessing non-excessive deformation of strands or core previous to the flexings, which would resist relative desired strand-movements for balancing, the balancing stresses are effective to the highest degree in shifting the strands into such balanced relations both with one another and with the core.

In some cases, as diagrammed at PO2, Figs. 1 and 10, the last processing stressing of the succession is an axial tensioning of greater magnitude than by PO1, (greater even than the highest tensioning in the last flexing between CD and PO1, Fig. 1), for the purpose of obtaining greater deformation of strands and core; PO2 being, as PO1 may be, any desired wire-rope pull-out or draw-off drum, but PO2 being so power-driven as to exert a more powerful pull than PO1, Fig. 10, on the assembled wire rope structure. In forms of the process wherein the greater axial tensioning by PO2 is employed, the multi-flexing treatment by the set of relatively small sheaves may be executed under such higher rope-tensioning as by PO2; but that is not preferred because such higher tensioning, acting to effect great strand-deformation, would oppose the best balancing operation by the multi-flexing, which as shown is most effective under the lower although powerful tensionings in Fig. 1 between CD and

PO1. Preferably, as shown in Fig. 1, the multi-flexing is executed under the lower tensioning by PO1 because of the lower strand-tensioning caused by PO1 at the flexings than by PO2, such 5 lower stresses providing greater freedom of the strands for their relative shifting balancing movements during the multi-flexing. The axial tensioning between CD and the first flexing at 1, desirably low as above, of course is much less 10 when the multi-flexing is executed under the pull by PO1 than when under the more powerful pull by PO2, as is desirable in avoiding premature deformation.

Thus, for the purpose of effecting balanced relations and inert condition in a wire rope having a hemp-rope or fiber core, (1) the wire rope treated is preferably one having substantially the non-inert condition of the "ordinary" type as emerging from CD, (2) the rope is subjected successively to a plurality of tensionings preferably also (3) including flexings preferably (4) under the tensioning of PO1 and preferably (5) as early as practicable after emergence from CD and preferably (6) under stressings of progressively 25 increasing magnitude, in order to effect the balancing and inertness while avoiding premature deformation opposing desired balancing and yet effecting substantial inertness simultaneous with the balancing treatment as a whole; the ultimate 30 deepness of the core-grooves corresponding with both the objectives of strand-inertness and balanced relations of strands to core, for the deeper the core-grooves produced by multi-flexing the better the relations of balance between strands 35 and the commercial irregular fiber core; the balanced relations of strands to strands being effected largely by the earlier, less heavy stresses before optimum strand-deformation by the co-operation of the greater core-resistance and 40 higher strand-tensionings of the later, heavier tensionings. Greater deformations and inertness in a wire rope having a fiber core are produced by the successive treatments of Fig. 1 including the multi-flexing between CD and PO1 and the 45 higher tensioning by PO2, the latter as shown preferably being, when used, in continuous process with the multi-flexing to avoid intermediate handling; and the greater strand-deformation in any case resulting from the combination of 50 the later heavier strand-tensionings together with the higher core-resistance to strand-compressions on the core by such heavier strand-tensionings.

Results similar to those of the processings of 55 Fig. 1 are produced by the different form of successive stressings diagrammed in Fig. 10 which includes the succession of progressively increasing tensionings of Fig. 1 but without the flexings between CD and PO1; the first step in Fig. 10 60 being the axial tensioning between CD and PO1 upon the wire rope in its condition of emergence from CD, such tensioning being low relative to the subsequent tensioning by PO2, and such later, higher tensioning by PO2 being the other step 65 of the series of stressings of progressively increasing magnitude; PO2 being any power-driven drum such as has been used heretofore to pull wire-rope structures assembled in CD from CD to the shipping-reel or wind-up reel at right, 70 Fig. 10; the drum or drums PO2 of course being driven at the rate producing the desired tensioning higher than PO1. In Fig. 10, when the wire-assembly treated includes a fiber core, each tensioning step produces results in balancing and 75 deformations of strands and core similar in kind

to those of the flexings and tensionings of Fig. 1; but the flexings under the tensionings in Fig. 1 are more effective in producing the ironing and kneading operations. But as the effect of the higher tensioning as by PO2 in Figs. 10 and 1 5 than by PO1 in Fig. 1, the total strand-deformation by PO1 and PO2 can be made greater than by PO1 alone without PO2. The higher tensioning by PO2 causes more powerful strand-compressions on the core and they cause greater 10 strand-deformations against great radial resistance of center or core regardless of core-material. When desirable in the case of any wire rope structure to employ more than the two successive tensioning steps diagrammed in Fig. 10, 15 similar to the series of three successive tensionings causing the three flexings in Fig. 1 and for the similar purpose of producing better balancing in a given product, then a third power-driven pull-out may be located in Fig. 10 to receive the 20 assembled wire structure traveling from PO1 toward PO2, and driven at a rate causing its rope-tensioning to be higher than PO1 but lower than PO2, in analogy to the progressively increasing magnitude of the steps of tensioning in Fig. 1, 25 and in accord with the general principle of the invention of avoiding premature strand-deformation which would prevent desired balancing. In any case when the tensioning by the last drum, as PO2, may be so high as possibly to affect ad- 30 versely the operations in the preceding steps including assembling in CD, then such adverse effect can be prevented if desired by employing an ordinary snubbing drum SD with usual brake BK, which may be used even in addition to the em- 35 ployment of PO1 in the form as shown of the common multiple-groove, double drum, wire rope pull-out.

In Fig. 10 the application of the tensioning by PO2 as a continuous process with the assembling 40 in CD and with the tensioning of the assembly between CD and PO1, is even more desirable than is the continuity of tensioning in Fig. 1 by PO2 with the multi-flexing between CD and PO1, because in Fig. 10 there is less strand-deforma- 45 tion by the lower tensioning between CD and PO1 than in Fig. 1 between 3 and PO1, and the higher tensioning by PO2 is useful in Fig. 10 in effecting sufficiently great strand-deformation to produce sufficient inertness to withstand han- 50 dling.

For wire rope structures of the many previously existing different designs of the helical outer elements and of the various resilient materials for the center or core, and for wire rope structures 55 designed as to dimensions to be adapted for various different kinds of service, the particular modes of applying our processing stresses of ironing, tensioning or flexing, or both, illustrated in the drawings by way of example, may be widely 60 varied; and this applies also to the length of time of continuous application of a processing stress to the wire-rope assembly, as well as to the number of times processing stresses may be applied in succession to a wire rope structure of any 65 given design, and also to the intensity of the applied processing stress or stresses.

The wire-helix deformation effected by the heavier assembly-stressing hereof, with or without flexing and irrespective of core-material, are 70 sufficient to produce the desired inert characteristic in wire rope structures. The ultimate deformation of these outer helical elements of the assembly is illustrated in Figs. 3 and 9 by the wire-helix EV of substantial diameter as con- 75

trasted with the preferably straight outer elements S at left in Figs. 1 and 10 previous to assemblage in CD. In cases where strands of the "ordinary" type wire rope have been slightly deformed as completed heretofore (as by squeezing compression in CD with or without subsequent prolonged assembly-tensioning by PO1 as in Fig. 10 between CD and PO1), the effect of our processing is seen by comparison of A and EV, Fig. 9, where A indicates such slight helical metal-set deformation by CD, and where EV, as in Fig. 3, illustrates the helices of substantially greater diameter resulting from our processing. It is this increase of metal-set helix-deformation which marks the difference between the lack of inertness of the "ordinary" type as heretofore constructed, and on the other, the product of the processing hereof possessing ample inertness. Although helix EV is of much larger diameter than helix A, yet it is much smaller than helix B. Helices A and EV illustrate wire rope strands which have been removed from assembled wire rope structures, helix A having been removed from the "ordinary" type in its condition of emergence from CD, Figs. 1 and 10, and helix EV having been removed from one of our products, as Figs. 2 or 8, in their condition on drum PO1 Fig. 1, or on drum PO2 of Fig. 10, or on drum PO2 of Fig. 1. Each of helices A and EV before removal from their wire ropes was in the form at B, Fig. 9, i. e., of a diameter corresponding generally with that of the core. Upon their removal from their cores, however, helices A and EV have sprung back to their natural, inherent metal-set shapes. The lack of inertness of an "ordinary" wire rope is due to its inclusion of helices shaped to no greater helical diameter than A. In our production of the improved "ordinary" type including helices like EV, the helical diameter is ample for rope-inertness, especially with the cooperation of the permanently deformed deep core grooves GG when the assembly treated includes a center having the initial radial yieldability of a fiber core. By the processing hereof therefore, we retain the advantageous lack of excessive springiness which characterizes the "ordinary" type, while at the same time we obtain an ample extent of the inertness of the pre-formed type, to eliminate the excessive susceptibility to rope-faults which heretofore has characterized the "ordinary" type.

The above deformed strands EV and groove-deformed core in Figs. 3 and 5 respectively, are shown combined in assembly in Figs. 2 and 8 in wire ropes having fiber cores which constitute the larger percentages of wire rope structures.

In Figs. 2 and 8 also are shown the ideal or balanced relations of strands to strands, and of strands to core, as well as such relations can be illustrated by drawings, and especially by a cross-section. The fact is that the balanced relations produced by the processing hereof exist not merely at occasional cross-sections of the processed rope as in Figs. 2 and 8, but they exist continuously throughout its length, because all of the processing stresses are applied, in succession, to each and every portion of the rope-length as it travels through the successive stages of the process from CD. In the multi-flexing process of Fig. 1 this is particularly the case because said multi-flexing preferably is a process which as a whole is a step of a process continuous with the operation of assemblage in CD, because the actions included in the multi-flexing preferably include the interactions between CD

and the relatively small sheaves which are involved in the above relative longitudinal shifting strand-movements between CD and sheave 1 which constitute the initial ironing-back operation of the balancing treatment. Upon the ironing out of strand-slacks, the flexing stresses are applied in rapid succession to the same portion of the rope-length, so that all portions of rope-length are in symmetrical balanced relations as shown in Figs. 2 and 8. Thus thereby is balancing effected at all portions of the length of the treated wire rope, and the sections of Figs. 2 and 8, showing the actual, ideal, symmetrical relations of strands to strands and of strands to core, at one particular cross-section of the rope, serve to illustrate the conditions throughout the length of the wire rope. Fig. 6 shows the core R of a wire rope of Fig. 2 which has been subjected to long service throughout the normal longitudinally resilient life of the core and has survived that service without injury as the result of the balanced and inert (deformed) strands and core. This is indicated in Fig. 7 by the fact that, although as the result of the long service the core-grooves have become much deeper than those of the core of our perfected product in Figs. 2 and 5, as an accompaniment of the loss of longitudinal resilience during the long service, nevertheless such groove-deepening has continued symmetrically with the grooves GG in Figs. 2 and 5. Fig. 7 in elevation illustrates the same wire rope after the same long service, this figure showing the continued maintenance of the strands after long service free from development of rope-faults into injuries.

A criterion of an effective execution of the processing hereof may be either a wire rope having the novel constructions hereof, or a wire rope of the "ordinary" type as above and not having the previous characteristic inertness and non-balanced relations.

We have discovered that the above principal objects of balancing, and of deformation into inert conditions, can be produced without "killing" needed longitudinal service-resilience of the wire rope structure, or impairing it. On the other hand, the service life of processed wire rope having a fiber core can be increased because as above the nature of the process and product is such as to permit the use of a larger core than heretofore. For example, as to the highest or last stressing, as by PO2. This "higher axial tension", noted on Fig. 10, usefully may be much greater than is possible by any arrangement for assembling in CD without injury to the helical outer wires by die-compression by CD on the traveling assembly; and this highest tensioning by PO2, in Figs. 1 and 10, preferably, for effective metal-set helix-deformation, is at least a substantial fraction of the breaking strength or maximum service load for which any particular form of structure which may be in process of fabrication, was intended, and designed and adapted. In some cases the highest of these higher tensionings may be equal to or even may exceed the tensioning by the maximum service load for which a particular structure may have been designed. The values of this highest tensioning hereof are defined even more precisely by the following illustration of a structure designed to have a breaking strength of, say, twenty-five tons, in which case this higher tensioning than by PO1 will be effective in accordance with our invention if it be as low as of the order of say, three to five tons,—about, say, fifteen per cent

or more of said assumed breaking strength of the particular structure assumed for illustration. A tensioning even as low as such a small but substantial fraction of the breaking strength of the 5 structure is high as compared with the closing tension acting on the same assembly inside CD. But this highest tensioning by PO2, without injury to the assembled structure, and without causing alterations of the assembling operation 10 inside CD, may be even higher than the above, such as several times higher than even that smaller fraction (fifteen per cent) of the breaking strength of the structure. In fact, we have discovered that the highest tensionings hereof, 15 as by PO2, may be so high as to approximate half the breaking strength of the structure without impairing its longitudinal resilience needed for service. In general, however, these highest tensionings may be varied in value according to the 20 grade and construction of the particular form of "wire rope" structure being processed according to the invention, and according to the service requirements of any such form; and, in general, in practice, the highest tensionings do not exceed 25 the maximum stresses intended to be applied to the structure in service.

We claim:

1. The improvement in apparatus for making a wire rope-structure consisting of flexible but stiff 30 wire helices and a yieldable but radially resistant fiber-rope core, which includes, in combination with the closing die, the closing pull-out and the receiving apparatus, a second power-driven rotatable tensioning pull-out and a snubber therefor, both located between the first pull-out and the receiving apparatus; and a plurality of sheaves located between the closing die and the closing pull-out and constructed and arranged to apply a plurality of powerful bending stresses 40 to the rope-structure at closely successive portions of its length, as it travels from the closing die to the closing pull-out.

2. In a wire rope machine, a source of supply of wire rope, a draw-off drum for the wire rope, 45 a second draw-off drum for the wire rope positioned between the source of supply of wire rope and the other drum, and means for rotating the drums, the first mentioned drum tensioning the wire rope in appreciably greater amount than the 50 other drum.

3. In a wire rope machine, wire rope closing means, a draw-off drum for the wire rope, a second draw-off drum for the wire rope positioned 55 between the closing means and the other drum, and means for rotating the drums, the first mentioned drum tensioning the wire rope in an appreciably greater amount than the other drum.

4. In an apparatus for the manufacture of wire 60 rope structures having a plurality of substantially stiff but flexible outer wire elements bent into place at the squeezer onto and around a center element into helical shapes and thereby slightly deformed into metal-sets of small helical diameter, said apparatus being of the type including 65 the lay-plate and squeezer in relatively rotatable relations, and including the closing pull-out causing said bending and slight metal-set deformation at the squeezer, and including the wind-up reel receiving the completed rope-structure, the improvement 70 which includes a second power-driven pull-out located in the rope-path between the closing pull-out and the wind-up reel, and pulling the assembled rope-structure at a higher rate and corresponding tension more powerful than 75 the closing pull-out, thereby substantially in-

creasing the comparatively small metal-set diameter of the helices as deformed by the squeezer, and consequently decreasing their tendency to unravel away from the center element.

5. An improved wire rope structure having a 5 plurality of substantially stiff wire elements flexed around a center element into helices, and of the type characterized by having excessive 10 tendency to unraveling resulting from the formation of its helices by flexing at the squeezing die 10 onto and around the center element, the improved 15 rope-structure lacking such excessive tendency by virtue of the fact that its helices have a metal-set 15 diameter substantially larger than that of their initial metal-set deformation effected by the squeezer.

6. An improved form of "ordinary" wire rope comprising a plurality of substantially stiff helical strands each comprising a plurality of helical wires stranded together, and a fiber rope core, to 20 inequalities of which the helical strands are adapted as characteristic of the production-method of "ordinary" wire rope consisting in forming the helices by bending them into the core, the improved form however, lacking the excessive 25 unraveling tendency characteristic of prior forms of "ordinary" rope by virtue of the fact that its helices have a metal-set diameter substantially larger than that of their initial 30 metal-set deformation by the squeezer in said characteristic production-method of "ordinary" wire rope.

7. The improvement in the manufacture of wire rope structures of the type including a plurality of substantially stiff outer wire elements 35 flexed into place onto the center element by the squeezer into helices, said improvement consisting in subjecting the rope-structure, subsequent to its assembly by such flexing at the squeezer, and during its travel from the closing pull-out to 40 the wind-up reel, progressively to a powerful pulling and axial tensioning which deforms the stiff outer wire helices into metal-set helices of substantially larger diameter than the helical metal-set of the initial deformation by the 45 squeezer.

8. In an apparatus for the manufacture of improved "ordinary" wire rope structures, the combination with apparatus for bending the outer wire elements into place onto and around a center element into helical shapes, said apparatus including a squeezer and closing pull-out; of a wind-up reel and a second power-driven pull-out between the wind-up reel and the closing pull-out and subjecting the rope structure to 55 higher axial tension than the closing pull-out; and a plurality of sheaves of small diameters in close succession between the squeezer and the closing pull out and offset from one another, for subjecting each portion of the travelling rope-structure to a rapid succession of sharp bendings in different directions at long rope-arcs, constituting a kneading treatment putting the rope-elements in balanced stress-relations with one another before the rope-structure travels beyond the closing pull-out to the field of more powerful action of said second power-driven pull-out.

9. In an apparatus for the manufacture of improved "ordinary" wire rope structures, the combination with apparatus for bending the outer wire elements into place onto and around a center element in helical shapes, said apparatus including a squeezer and a closing pull-out; of a wind-up reel and a second power-driven pull- 70 75

out between the wind-up reel and the closing pull-out and subjecting the rope structure to higher axial tension than the closing pull-out, setting the elements in conditions substantially 5 eliminating tendencies to unraveling; and kneading means between the squeezer and closing pull-out and working the rope-elements together into balanced stress relations with one another before the rope-structure is acted on by the higher 10 tension of said second pull-out whereby when the latter sets the elements it sets them in the balanced stress relations effectuated by said kneading means.

10. In the manufacture of "ordinary" wire 15 rope structure, the method of treatment after the bending of its outer wire elements by the squeezer onto the center element into helices, which consists in subjecting the rope to an axial tensioning so high that the metal-set of the 20 helices by the squeezer is further deformed into a substantially larger metal-set helical diameter substantially reducing the unravelling tendency of the rope structure, and in subjecting the rope structure, previous to the application of said high 25 tensioning and under a condition of lower tensioning, to a kneading and ironing treatment which puts the rope-elements in balanced stress relations with one another, whereby when they thereafter are set by said higher tensioning they 30 are set in said balanced stress relations effectuated by said kneading and ironing treatment.

11. The improved form of "ordinary" wire rope 35 characteristically having its plurality of multi-wire strands and its fiber core in unbalanced stress relations with one another, and its strand-helices so insecurely set as to possess excessive tendency to unravel, the strand-helices of said improved form having an abnormally large deformed metal-set helical diameter not practicable 40 to be effected by the initial bending of the strands helically onto the core, which large metal-set diameter of the strands sets them securely in a condition of substantial reduction of said unravelling tendency; and said abnormally large deformed metal-set helical diameter being substantially 45 smaller than the actual diameter of the helices as they extend around the core whereby the helices so securely set are in balanced stress relations to one another and the fiber core.

50 12. The improved form of "ordinary" wire rope structure, which like prior forms of the same, has a metal-set helical diameter of its outer wire elements which is substantially less than the actual helical diameters of the elements extending around the core and which metal-set diameter is characteristic of the formation of the strands of "ordinary" wire rope structures by being bent directly onto the core into helices and which causes the undesirable excessive unravelling 55 tendency of "ordinary" wire rope structures and causes the desirable adaptation of the helices to inequalities of the core; the metal-set helical diameter of the helices of the improved form of "ordinary" rope being substantially greater than is practicable to be effected by the squeezer, causing substantial decrease of the undesirable unravelling 60 tendency, and substantial increase of the desirable adaptation of the helices to inequalities of the core.

65 13. The improvement upon "ordinary" wire rope structures wherein the multiple-wire helices tend powerfully to straighten out and cause unravelling, owing to the bending of the wire elements 70 onto the center element into helices instead of

pre-forming the helices before assembly with said center, said improvement consisting of a condition of the wire-helices which substantially reduces their tendency to straighten out and cause unravelling, said condition being a metal set of said helices in substantially larger diameters than is practicable to be effected by said bending onto the center. 5

14. The improved form of "ordinary" wire rope 10 structure which consists of a permanent setting of the elements in a condition substantially decreasing the excessive tendency to unravelling which is characteristic of previous forms of the "ordinary" type, and substantially improving the unbalanced stress relations which are characteristic 15 of such previous forms, said setting being substantially dependent for said improvements, upon the novel condition of the wire-helices in a substantially large metal set diameter which is substantially intermediate their straight metal 20 set condition before assembly with the center element, and their actual helical diameter as they extend about the center in the rope structure, said metal-set diameter being larger than is practicable to be effected by the squeezer. 25

15. The improved form of "ordinary" wire rope 30 structure which consists fundamentally of a metal setting of the wire-helices in a helical diameter substantially larger than is practicable to be effected by bending into helices onto the center at the squeezer, but substantially smaller than the actual diameter of the helices as they extend around the center element; said relatively great size of said diameter substantially decreasing the tendency to unravelling of prior forms of 35 the "ordinary" type; said relatively small size of said diameter preserving that lack of excessive setting which is characteristic of "ordinary" wire rope structures by which the wire elements can be adapted to inequalities of the center; and 40 said metal set diameter being accompanied by balanced stress relations of the wire-helices with one another and the center as the result of its said relative smallness of helical diameter and consequent lack of over-setting. 45

16. A wire rope structure of the "ordinary" 50 type but improved by the feature of having its helical elements metal-set into substantially increased diameter beyond that practicable to be effected by bending into helices onto the center at the squeezer, which increased diameter substantially reduces the tendency to unravelling heretofore possessed by "ordinary" wire rope structures, and further improved by the feature of the helical elements being in balanced stress relations to one another and to the center elements, and yet further improved by the feature of the helices and center being permanently set in their said balanced stress relations by means of said metal-set diameter of the helices. 60

17. As an improvement over both "pre-formed" 65 wire rope structures and previous forms of "ordinary" wire rope structures, the product consisting of multiple-wire helices laid and closed on a fiber core, and wherein the helices and core are in balanced stress relations to one another and are set in said relations by means of a metal-set diameter of the helices of an increased size beyond that practicable to be effected by bending into helices onto the center by the squeezer, 70 but not too large, providing both for said balanced relations, not possible in the "pre-formed" type, and providing also against the excessive tendency to unravelling which is characteristic of prior forms of the "ordinary" type. 75

18. The improvement in the manufacture of "ordinary" wire rope structures, which consists in subjecting such structure, after the bending of the wire elements onto the center element into helices, to a plurality of powerful stressings successively applied, progressively increasing in power, successively causing smaller amounts of improvement in the balanced stress relations of the rope-elements, but successively causing greater amounts of improvement in the metal-set condition of the helices by way of increases in the metal-set diameters of the helices; a later one of the stressing more securely setting the rope-elements in the balanced stress relations effected by the preceding stressing, than the preceding stressing itself.

19. The improvement in the manufacture of wire rope structure which consists in treating a rope structure of which the wire helices have been formed by bending them onto a center element at the squeezer by subjecting such rope-structure as it travels away from the squeezer toward the wind-up reel to a powerful stressing which substantially improves the balanced stress relations of the rope-elements, and substantially increases the metal-set diameter of the wire helices, thereby substantially decreasing the unraveling tendency which is characteristic of the formation of the helices by bending the wire elements onto the center element.

20. The method of manufacturing an improved form of the type of wire rope structure which is produced by bending substantially stiff wire elements onto a center element by a squeezing die into helices, which consists in subjecting such rope structure to tensioning of a substantial fraction of the breaking strength of the structure and amounting to a pull of the order of tons, thereby effecting a substantial increase of the metal-set diameter of the helices above that effected at the squeezer, and effecting a corresponding decrease of the unraveling tendency characteristic of rope-structures having helices formed by bending onto the center element.

21. The method of manufacturing a wire rope structure of the type wherein the wire helices are formed by bending the wire elements onto the center element in the squeezer, and wherein the helices are substantially stiff, consisting of a multiplicity of wires stranded together, said method consisting in subjecting the rope-structure, subsequent to its assembly by such bending at the squeezer, and during its travel toward the wind-up reel, to powerful tensioning deforming its elements into a substantially increased metal-set diameter above the metal-set diameter effected by the bending at the squeezer.

22. The improved wire rope structure of the type having substantially stiff wire elements formed into helices by being flexed by a squeezer onto a center element and thereby only slightly deformed, and having the characteristic feature of that type, of a tendency to unraveling, but lacking the characteristic feature of that type heretofore, of unbalanced stress relations of the rope-elements, the improved rope-structure being characterized by a metal-set diameter of its helices substantially greater than that practicable to be effected by deformation at the squeezer, accompanied by a corresponding decrease of the

tendency to unraveling and by a decrease of the unbalanced stress relations of the rope-elements.

23. The method of manufacturing a wire rope structure having balanced stress relations of substantially stiff multiple-wire strands and a diametrically yieldable core, which consists in treating such a rope of which the strands possess only a small metal-set diameter, by subjecting it to a comparatively low pull increasing said small metal-set diameter to a not excessive extent; and subjecting the rope structure so pulled to a powerful kneading treatment working the strands and core together back and forth under such low pull into balanced stress relations with one another, said kneading and balancing treatment being characterized by a rapid succession at each successive portion of the pulled rope, of sharp flexings at relatively long rope-arcs and in different directions.

24. The improvement in apparatus for making comparatively stiff "ordinary" wire rope structures having a center of fiber rope and a plurality of substantially stiff but flexible outer wire elements bent into place onto the rope center into helices, said apparatus being of the type including the lay-plate and the squeezer in relatively rotatable relations, and the closing pull-out causing said bending of the stiff wire elements at the squeezer; and said improvement including a plurality of sheaves arranged for successive operation on the assembled rope-structure being pulled from the squeezer and then having unbalanced stress relations of its elements, said operation constituting a kneading and working together of the stiff wire elements and fiber rope center into balanced stress relations with one another, said plurality of sheaves being substantially dependent for their said kneading effect upon and including (1) an off-setting of the sheaves from one another providing for long peripheral arcs of contact with the traveling rope-structure, (2) comparatively small diameters of the sheaves providing for relatively sharp bendings of the traveling rope-structure at such long contact-arcs, and (3) a substantially close succession of the sheaves providing for rapidly successive action upon each successive portion of the traveling rope-structure; said off-setting providing also for successive bendings in different directions, all whereby each portion of the stiff traveling rope-structure is subjected to a rapid succession of sharp bendings in different directions at long rope-arcs, constituting the kneading operation by said arrangement of sheaves which balances the rope-elements.

25. The improvement in the manufacture of wire rope structures of the type including a plurality of substantially stiff yet flexible outer wire elements bent into place onto the center element by a squeezer into helices, said improvement consisting in subjecting the rope-structure, subsequent to its assembly by such bending at the squeezer and during its travel away from the squeezer toward the wind-up reel, progressively to powerful stressing deforming its elements to a substantial extent greater than is possible at the squeezer, including the deformation of the helices to a metal-set diameter substantially larger than that possible at the squeezer.
